UNITED STATES PATENT OFFICE.

GEORGE C. JENSEN, OF OAKLAND, CALIFORNIA.

SHIFT-BLOCK LOCK AND RETAINER.

1,348,802.

Specification of Letters Patent.

Patented Aug. 3, 1920.

Application filed November 12, 1919. Serial No. 337,548.

To all whom it may concern:

Be it known that I, GEORGE C. JENSEN, a citizen of the United States, residing at Oakland, in the county of Alameda and 5 State of California, have invented certain new and useful Improvements in Shift-Block Locks and Retainers, of which the following is a specification.

The present invention relates to an improved form of device adapted for association with a pair of shifter blocks which are longitudinally movable on supports and the principal objects are to provide a construction which is preferably carried by the gear 10 15 case cover and which is operated by the movement of the means for selectively moving the blocks whereby the blocks are capable of being retained in their adjusted position, one locked from movement during 20 the movement of the other, and both locked from movement when desired.

The invention consists primarily in the incorporation or provision of a pair of independently movable pivotally mounted 25 arms adapted for actuation by the movement of the means for controlling the shifting of the blocks for coöperating with the blocks and a means for coöperation with said pivoted arms to prevent movement thereof by the means for selectively operating the blocks. Another feature is to provide a means whereby when the pivotally mounted members are held from movement that the same coöperate with a 30 35 member carried by the gear case, which precludes the removal of the cover from the case.

With the above mentioned and other objects in view the invention consists in the novel construction and combination of parts hereinafter described, illustrated in the accompanying drawings, and set forth in the claims hereto appended, it being understood that various changes in the form, 40 45 proportion, size and minor details of construction within the scope of the claims may be resorted to without departing from the spirit or sacrificing any of the advantages of the invention.

To more fully comprehend the invention, reference is directed to the accompanying drawings, wherein,

Figure 1 is a view in side elevation, partly in section, disclosing the preferred embodiment of my invention.

Fig. 2 is a transverse vertical sectional view taken on the line 2—2, Fig. 1.

Fig. 3 is a horizontal sectional view taken on the line 3—3 of Fig. 1.

Fig. 4 is a detailed sectional view taken 60 on the line 4—4 Fig. 1.

Fig. 5 is a view similar to Fig. 4 with a shifter block controlling lever moved to engagement with one of said blocks and free of the other block. 65

In the drawings wherein like characters of reference designate corresponding parts, 1 indicates a gear case within which is the transversely disposed block supporting rod 2 on which are mounted for selective move- 70 ment the shifter blocks 3, depending from which are the forks 4 for engaging the gears to be shifted. The blocks are arranged on the rod end to end, and upwardly from the same extend the arms 5 preferably positioned at adjacent ends of the blocks 3, and each extending beyond the end of its associated block to overlap the other. Each of the arms 5 is formed in its upper surface with a notch 6 which are adapted to lie 80 parallel on the movement of the blocks 3 to position the gears controlled thereby in non-power transmitting or neutral position, and into said notches is adapted to extend the lower end 7 of a block operating lever 8 85 fulcrumed for universal swinging movement in a cover 9, adapted to rest on and close the upper open top of the case 1. The lever 8 when in its vertical or non-operating position is adapted to lie with the lower 90 end 7 seated within both notches 6 as in Figs. 3 and 4 of the drawings, and when it is desired to operate one of said blocks the lever is moved laterally on its fulcrum to position the lower end 7 thereof in full engagement with one of the said notches 6, 95 and removed from the other notch 6, as in Fig. 5 of the drawings. The arms 5 are formed on their outer face and at each side of the respective notches 6 with the speed 100 stops 10, Figs. 1, 2 and 3 of the drawings. Mounted on the interior of the cover 9, are the levers 11, fulcrumed at one end on the vertically disposed bolt 12 and their body portions adapted to extend one on 105 either side of the outer face of the respective arms 5, the free ends of said levers being bent toward each other as at 13 and the terminal end portions beyond said bends being disposed in alinement with the body 110

portion of the opposing lever as at 14. This construction provides the crossing or overlapping of the free ends of the levers 11 illustrated in Fig. 3 of the drawings, said 5 free ends lying in spaced relation. The free ends of the levers 11 are normally drawn toward each other and maintained under spring tension from separation by a coiled spring 15 secured at its opposite ends in the 10 respective levers 11, Figs. 1 and 3 of the drawings. Depending from the under side of the lever 11 preferably in the center of their main body portion and adjacent their inner edge are the downwardly extending 15 lugs 16, each of a configuration corresponding to the recess 6, Fig. 1 of the drawings, and said lugs each carries on its inner face a member 17 preferably formed with a rounded head. On the lateral movement of 20 the lower end 7 of the lever 8 to position the same in full engagement with one of the notches 6 to operate the block associated with said notch, as in Fig. 5, one side of the end of the lever 7 will coöperate 25 with the member 17 associated with the lever 11 of the block engaged by the lever 7, and the spring 15 will act on the opposing lever 11 to move its lug in full engagement with its notch 6, Fig. 5 of the drawings, which movement will retain one of the 30 blocks 3 in its neutral position and prevent movement thereof.

On the longitudinal movement of the engaged block by the operation of the lever 7, 35 the lower end of the lever will ride from a member 17 and permit said member 17 to contact with the face of the arm 6 of the moved block to seat within one of the speed stops 10 when the same is moved into line 40 therewith due to the operation of the block. This yielding movement of the lever 11 is accomplished by the spring 15. It will be understood that on the movement of the lower end of the lever 7 from one of the 45 notches 6, said notch is immediately engaged by the lug on its associated lever 11, and is precluded from movement, and that the block when moved by the operation of the lever 8 is held in its adjusted position 50 by the engagement of the member 17 with one of the speed stops 10 thereof. Thus an interlock and retainer is provided for each of the blocks 3.

By this construction it is also possible to 55 lock the blocks from operative movement by the lever 8, and to accomplish this result I prefer to employ a locking bolt or plunger 18 longitudinally movable in an open ended bore 19 in the cover 9 and arranged when 60 said bolt is in its depressed position to have the lower end thereof project between the terminal extensions 14 and the levers 11, and thus preclude movement of said levers on their fulcrum 12, at which time the lower 65 end 7 of the lever 8 is held in the position

indicated in Fig. 4 in engagement with both notches 6 of adjacent arms 5 and being prevented from lateral movement, thus locks the blocks in their adjusted position.

The locking bolt 18 carries at its upper 70 end the key-releasing lock mechanism 20, which operates the latch 21 coöperating with the depression 22 when the plunger is in its depressed position, the plunger being normally raised by the action of the coiled 75 spring 23 mounted in the bore 19.

In the present construction, the cover 9 is capable of being locked on a case at such time as the bolt 18 is in its depressed position, and in accomplishing this result I provide the flanged arms 24, one extending upwardly from the case 1 at opposite sides of the levers 11, Figs. 2 and 3 of the drawings, and the flanged ends of said arms are adapted to overlie said levers 11 until such time 85 as the levers are pressed inwardly toward each other, which is only possible when the locking bolt 18 is in its released position, and the operating lever 8 is removed from the cover 9. 90

It will be apparent that in the present construction I provide a pair of pivoted arms embracing the shifter blocks and incorporate with said arms spring means whereby the arms serve as retainers for 95 holding the blocks in their adjusted position and also associate with levers 11 a means for preventing simultaneous or independent movement of said levers 11 on their fulcrum, thus locking the blocks 100 against movement by the operating lever 8.

Having thus described my invention what I claim is:

1. In combination with a supporting rod, a pair of independently movable shifter 105 blocks thereon arranged in end to end relation and each provided with an operating lever receiving recess, an operating lever coöperating with the lever receiving recesses for selectively operating said blocks, a pair 110 of levers one associated with each shifter block and fulcrumed to swing transversely of the plane of movement of said blocks, means for locking said pair of levers from pivotal movement relatively to said blocks 115 whereby the same engage said operating lever and maintain the same in the recess of both blocks thereby locking said blocks from movement.

2. In combination with a pair of shifter 120 blocks mounted for independent movement on a single shaft and each provided with an upstanding arm, each formed with an operating lever receiving recess, an operating lever coöperating with the lever receiving 125 recesses for selectively operating said blocks, a pair of levers embracing the lower end of said operating lever and capable of independent movement by said operating lever in a plane transversely of the plane of move- 130

- ment of said blocks on the movement of said operating lever from the recess of one block into the recess of the other, and means for locking said pair of levers from movement 5 to retain said operating lever in the recesses of both blocks.
3. In combination with a pair of independently movable shifter devices provided with speed stops and a lever receiving recess, 10 an operating lever coöperating with said recesses and adapted for lateral movement from one recess to another for selectively operating said shifter devices, a pair of levers one coöperating with each shifter device 15 and fulcrumed at adjacent ends to swing laterally of said devices, means for yieldably forcing said arms together toward said shifter devices, means on each lever for co-operating with the speed stop of its associated shifter device to retain the shifter device in its set position, said means adapted 20 for engaging with the recess of one shifter device on the movement of the operating lever therefrom into full engagement with the recess of the other shifter device whereby one of said shifter devices is locked from movement during the movement of the other device from a predetermined position, and means coöperating with the free ends of 25 said levers to prevent lateral movement thereof whereby said shifter devices are locked from operative movement.
4. In combination with a pair of independently movable shifter devices each provided with an operating lever receiving recess, a fulcrumed operating lever normally coöperating with both of said recesses and adapted for lateral movement from one recess to another for selectively operating said 30 shifter devices, a pair of levers embracing said shifter lever below its point of fulcrum, said levers fulcrumed at adjacent ends to swing laterally with said shifter lever, and means for coöperating with the free ends of 35 said pair of levers for locking the same from lateral movement whereby said shifter lever is held in position to coöperate with both of said recesses thereby locking said shifter devices from movement.
5. In combination with a gear case provided with a pair of independently movable shifter devices, a cover for said case, a shifter lever carried thereby for independently operating said shifter devices, a pair 40 of spring held levers one coöperating with each shifter device, said levers each fulcrumed at one end to said cover to swing laterally of said shifter devices and adapted for frictionally engaging the associated devices to retain the same in their adjusted 45 position and one to engage its associated device to hold the same from movement during the operative movement of the other shifter device, and a lock controlled member 50 carried by the cover for coöperating with

the free ends of said levers to lock the same from lateral movement and preclude movement of said shifter devices.

6. In combination with a gear case provided with a pair of shifter devices therein 70 independently movable in a parallel plane, a shifter lever for independently operating said shifter devices, a pair of spring held levers within said case one coöperating with each shifter device and longitudinally of 75 which said shifter devices are movable, a fulcrum associated with the corresponding ends of each lever of said pair to permit the same to swing laterally of said shifter devices, said levers adapted for frictionally 80 engaging their associated shifter devices to retain the same in their adjusted position and one to engage its associated device to hold the same from movement during the operative movement of the other shifter device, and a lock controlled bolt capable of movement to engage the free ends of said levers to lock the same from lateral swinging movement and preclude movement of 85 said shifter devices. 90

7. In combination with a gear case provided with a supporting shaft, a pair of shifter blocks mounted thereon for independent movement and provided with upwardly extending arms one overhanging the adjacent block, said arms being each provided in its surface with a notch and one or more speed stops, a shifter lever for independently operating said shifter devices, a pair of spring held levers within said case, one coöperating with each block arm and longitudinally of which said blocks are movable, said levers being fulcrumed at corresponding ends to swing laterally of said arms and provided with means adapted to frictionally 100 engage the speed stops of the respective arms to retain said blocks in their adjusted position and for reception within the notch of their respective arms to hold their associated blocks from movement on the movement of the other block from a predetermined position, and means for locking the free ends of 105 said levers from swinging movement whereby operative movement of said blocks is precluded. 110

8. In combination with a gear case provided with a supporting shaft, a pair of shifter blocks mounted thereon for independent movement longitudinally thereof and each provided with an upwardly extended arm each overlying the other block, said arms being each formed with a notch and one or more speed stops, a shifter lever for independently operating said shifter devices, a pair of spring held levers one coöperating 120 with each block and longitudinally of which said blocks are movable, said levers mounted at one end to swing on a common fulcrum and arranged with their free ends crossing and disposed in alinement with each other, 125 130

and a lock controlled locking bolt adapted for extending between the crossed free ends of said levers to prevent lateral movement thereof and to lock said shifter blocks in their adjusted position.

9. In combination with a gear case provided with a pair of shifter devices, a cover for the case, a lever for selectively operating said devices, a pair of pivoted levers carried by said cover for locking said devices in their adjusted position, a pair of flanged members on said case for overlying said levers, and means for locking said levers from swinging movement and to lie beneath said overlying members whereby said shifter devices are locked from movement and said cover is locked to said case.

10. In combination with a pair of independently movable shifter blocks each provided with an operating lever receiving recess, an operating lever coöperating with the lever receiving recesses for selectively operating said blocks, a lever associated with each shifter block and fulcrumed to swing transversely of the plane of movement of said blocks, means for locking said levers from pivotal movement relative to said blocks, whereby the same engage said recesses of both blocks thereby locking said blocks from movement.

11. In combination with a gear case pro-

vided with a pair of shifter devices, a cover for the case, a lever for selectively operating said devices, a pair of pivoted levers carried by said cover for locking said devices in their adjusted position, said case provided with means for coöperating with said levers and means for locking said levers from swinging movement and to engage with said coöperating means whereby said shifter devices are locked from movement and said cover is locked to said case.

12. In combination with a pair of independently movable shifter blocks, each provided with an operating lever receiving recess, an operating lever coöperating with the respective lever receiving recesses for selectively operating said blocks, a pair of spring held levers, one coöperating with each block and fulcrumed to swing transversely of the plane of movement of said blocks, said levers adapted for retaining the blocks in their selectively operative positions, and means for locking the levers from operative movement to lock said blocks from movement.

In testimony whereof I have signed my name to this specification in the presence of a subscribing witness.

GEORGE C. JENSEN.
